UNITED STATES PATENT OFFICE.

IVEN LODGE, OF RUSSELL, IOWA.

SULKY-PLOW.

SPECIFICATION forming part of Letters Patent No. 257,502, dated May 9, 1882.

Application filed December 13, 1881. (No model.)

To all whom it may concern:

Be it known that I, IVEN LODGE, a citizen of the United States, residing at Russell, in the county of Lucas and State of Iowa, have 5 invented certain new and useful Improvements in Attachments for Sulky-Plows; and I do hereby declare the following to be a full, clear, and exact description of the invention, such as will enable others skilled in the art to which 10 it appertains to make and use the same, reference being had to the accompanying drawings, and to the letters or figures of reference marked thereon, which form a part of this specification.

My invention relates to that class of cultivators or sulky-plows in which means are provided for varying the width cultivated by the machine, for regulating its draft, and for raising and lowering the frame carrying the plows when turning or guiding; and it consists in 15 the details of construction and general arrangement of parts, all as will be hereinafter fully described, and pointed out in the claim.

In the drawings, Figure 1 represents a top plan view of my improved machine; Fig. 2, a 20 transverse section taken on the line $y-y$ of Fig. 1, and Fig. 3 a similar view taken on the same line of Fig. 1, in an opposite direction.

Similar letters of reference occurring on the several figures indicate like parts.

30 The frame of my improved machine is formed in two parts, $A A'$, which are connected together at the top on each side by the sectors B , said frame being adapted to slide up and down in recesses a , formed down through the 35 base b of the vertical gears C , to which base are journaled the wheels D , as fully shown in the drawings.

Upon each side of the main frame are journaled the lifting-levers E , which carry upon 40 their inner ends the segmental cog-wheels e , the teeth of which engage with the cogs of the vertical gears C , said levers E being provided with the spring-detents d , which fit into the notches of the sectors B , to hold the levers in 45 any desired position. It will thus be seen that the frame $A A'$ may be readily raised or lowered for the purpose of turning the machine, or for clearing the plows from obstructions, by operating the levers E , thereby causing the 50 segmental gears e , carrying said frame, to engage with the cogs of the vertical gears C at either or both sides, as the occasion may require, and move up or down upon the same, ac-

cording to the direction in which the said levers are depressed.

55 F represents a bail or rock-shaft, journaled in the lower ends of the frame $A A'$ on each side, which carries the frog G , to which is attached the plow-beam H , as fully shown in Fig. 2.

60 Lugs e are provided on each side of the frog G to receive and hold the lower ends of the forked rod I , which is connected at the top to the elbow-lever J , said lever being pivoted to a projection, f , upon the sector K , which is rigidly attached to the frame A and provided with notches h , adapted to receive the spring-detent g of the said lever to hold it in the desired position.

65 By means of the lever J the bail or shaft F , carrying the plow-beam, may be raised or lowered to regulate the depth of the plow according to the nature of the work, and to hold it in the desired position.

70 The plow or plows can be easily changed from right to left, as may be deemed necessary.

75 A suitable seat is attached to the upper part of the frame A and a rigid iron frame, M , secured to the lower front part of the frame, as fully shown in the drawings.

80 The several parts composing the skeleton frame of the machine are preferably of iron, thereby dispensing with the cumbrous wooden frames commonly used, and the mechanism employed for operating the machine is of so 85 simple a nature as to render the replacement of the several parts an easy matter in case of breakage.

85 My invention is not only adapted for use as a sulky-plow, but may be used equally as well 90 in connection with cultivators of any kind, or with stalk-cutters.

Having thus described my invention, what I claim as new and useful is—

95 The combination, with the frame $A A' B$, of the sector-plate K , elbow-lever J , hooked and forked connecting-rod I , beam-clamp or saddle G , having eyes e , and plow-bail F , substantially as shown and described.

100 In testimony whereof I affix my signature in presence of two witnesses.

IVEN LODGE.
